UNITED STATES PATENT OFFICE

161,630

PAPER NAPKIN DISPENSER

Morris Housen, Erving, Mass., assignor to Erving
Paper Mills, a corporation of Massachusetts

Application December 17, 1949, Serial No. 6,682

Term of patent 14 years

(Cl. D52—2)

To all whom it may concern:

Be it known that Morris Housen, a citizen of the United States, residing at Erving, in the county of Franklin and State of Massachusetts, has invented a new, original, and ornamental Design for a Paper Napkin Dispenser, of which the following is a specification, reference being had to the accompanying drawing, forming part thereof.

Fig. 1 is a perspective view;

Fig. 2 is a view in front elevation on a reduced scale; and

Fig. 3 is a view in side elevation of a paper napkin dispenser showing my new design.

I claim:

The ornamental design for a paper napkin dispenser, as shown.

MORRIS HOUSEN.
